(57) **CLAIM**

The ornamental design for a cat scratcher as shown and described.

DESCRIPTION

FIG. 1 is a perspective view of a cat scratcher that consists of four identical parts;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of one of the identical sections thereof;

FIG. 9 is a perspective view of two of the identical sections thereof in an alternate configuration; and,

FIG. 10 is an exploded view of FIG. 9.
